Primary Examiner — Amy C Wierenga

CLAIM

The ornamental design for a quick hose connector assembly, as shown and described.

DESCRIPTION

FIG. 1 is a front view of a first part of a quick hose connector assembly shown disassembled;

FIG. 2 is a back view of the first part thereof shown disassembled;

FIG. 3 is a left view of the first part thereof shown disassembled;

FIG. 4 is a right view of the first part thereof shown disassembled;

FIG. 5 is a top view of the first part thereof shown disassembled;

FIG. 6 is a bottom view of the first part thereof shown disassembled;

FIG. 7 is a perspective view of the first part thereof, shown disassembled;

FIG. 8 is a front view of a second part of the quick hose connector assembly shown disassembled;

FIG. 9 is a back view of the second part thereof shown disassembled;

FIG. 10 is a left view of the second part thereof shown disassembled;

FIG. 11 is a right view of the second part thereof shown disassembled;

FIG. 12 is a top view of the second part thereof shown disassembled;

FIG. 13 is a bottom view of the second part thereof shown disassembled;

FIG. 14 is a perspective view of the second part thereof shown disassembled;

FIG. 15 is a front view of the quick hose connector assembly shown assembled, showing my new design;

FIG. 16 is a back view of the quick hose connector assembly, shown assembled;

FIG. 17 is a left view of the quick hose connector assembly, shown assembled;

FIG. 18 is a right view of the quick hose connector assembly, shown assembled;

FIG. 19 is a top view of the quick hose connector assembly, shown assembled;

FIG. 20 is a bottom view of the quick hose connector assembly, shown assembled;

FIG. 21 is a perspective view of the quick hose connector assembly, shown assembled; and,

FIG. 22 is a perspective view of the first and second parts of the quick hose connector assembly to be assembled together and shown disassembled.

(Continued)

The broke lines illustrate portions of the quick hose connector assembly that form no part of the claimed design.
